UNITED STATES PATENT OFFICE

HARRY W. HICKS, OF BROOKLINE, MASSACHUSETTS

DESIGN FOR A COLLAPSIBLE TUBE

Application filed April 3, 1931. Serial No. 39,358. Term of patent 14 years.

To all whom it may concern:

Be it known that I, HARRY W. HICKS, a citizen of the United States, residing at Brookline, in the county of Norfolk and State of Massachusetts, have invented a new, original, and ornamental Design for a Collapsible Tube, of which the following is a specification, reference being had to the accompanying drawing, forming a part thereof, of which—

The figure is an elevation of a collapsible tube showing my new design, the dominant feature of the design residing in the cap of the tube.

I claim:

The ornamental design for a collapsible tube, as shown and described.

HARRY W. HICKS.
